UNITED STATES PATENT OFFICE.

ARTHUR W. COX, OF BALLARD VALE, MASSACHUSETTS.

DESIGN FOR A TABLE-KNIFE.

SPECIFICATION forming part of Design No. 20,341, dated November 18, 1890.

Application filed October 18, 1890. Serial No. 368,606. Term of patent 14 years.

To all whom it may concern:

Be it known that I, ARTHUR W. COX, a citizen of the United States, residing at Ballard Vale, in the county of Essex and State of Massachusetts, have invented certain new and useful Improvements in Designs for Double-Edge Table-Knives; and I do hereby declare the following to be a full, clear, and exact description of the invention, such as will enable others skilled in the art to which it appertains to make and use the same.

This invention relates to a novel design for table-knives; and it consists of the peculiar profile, which will be hereinafter more particularly described and claimed, and which is shown in the accompanying drawings, in which—

Figure 1 is a side elevation of a knife embodying my invention. Fig. 2 is an edge view. The knife comprises the blade A, shank B, the rest or bolster C, and handle D. The handle D is flattened and its edges slope from the rear end thereof to the base of the rest or bolster C. The shank B is long and forms a

continuation of the outline of the handle, as indicated by the dotted lines in the drawings. The blade A is nearly circular in form, and is in the plane of the handle D—*i. e.*, the greatest diameter of the flattened portion of the handle extends in the same direction as the plane of the blade. The bolster or rest C projects an equal distance from the sides of the handle and the shank. The front wall *f* of the rest C is an ogee curve in profile, and the rear wall *g* curves outwardly and rearwardly. The two walls meet on a sharp edge.

Having thus described my invention, what I claim, and desire to secure by Letters Patent, is—

The design for a table-knife, substantially as herein described and shown.

In testimony whereof I affix my signature in the presence of two witnesses.

ARTHUR WATSON COX.

Witnesses:

CHARLES H. MARLAND,
H. J. GARDNER.
